UNITED STATES PATENT OFFICE.

WILLIAM BURROUGHS SMITH WHALEY, OF NEWTON, AND EDWARD P. ROBINSON, OF MALDEN, MASSACHUSETTS, ASSIGNORS TO REVERSIBLE GAS-ENGINE COMPANY, A CORPORATION OF MAINE.

INTERNAL-COMBUSTION ENGINE.

1,039,866.

Specification of Letters Patent.

Patented Oct. 1, 1912.

Application filed August 28, 1908. Serial No. 450,687.

To all whom it may concern:

Be it known that we, WILLIAM B. SMITH WHALEY and EDWARD P. ROBINSON, both citizens of the United States, and residents, respectively, of Newton, county of Middlesex, and State of Massachusetts, and of Malden, county of Middlesex, and State of Massachusetts, have invented an Improvement in Internal-Combustion Engines, of which the following description, in connection with the accompanying drawings, is a specification, like letters on the drawings representing like parts.

The present invention relates to an internal combustion engine, and is mainly embodied in the controlling mechanism which is used when the engine is to be started, the arrangement being such that all the necessary operations for starting are performed automatically by a single controlling device.

The arrangement is such that the parts which control the position of mechanism which actuates the inlet and exhaust valves, the ignition timer with its switch, and an auxiliary starting device, are so connected that they are moved to the proper position for starting the engine in either direction by one controlling or reversing lever. The auxiliary starting device which is herein shown for purposes of illustration consists of a traveling valve and distributing means which control a source of fluid pressure, such as compressed air, to be used if for any reason the engine fails to start by combustion, there being a stop valve interposed between the traveling valve and the supply tank or reservoir for compressed air, this stop valve being opened by hand when it is desired to bring the auxiliary starting device into operation. For convenience, this starting device will be hereinafter referred to as the auxiliary air-valve, and the operating parts thereof will be termed the valve, the distributing member, and the reversing member.

The auxiliary starting device which controls the operation of the fluid pressure comprises a distributing member having a number of stationary distributing ports communicating respectively with the cylinders, and a traveling valve having a single port which operates in unison with the half time shaft in a four cycle engine. The communi-

cation between the distributing member and the cylinders is through ducts which are independent of the regular inlets for the explosive mixture, and the valve is so arranged that the pressure is successively let into the cylinders substantially at the beginning of the expansion stroke, and when the regular inlet and exhaust valves of the cylinder are closed, so that the action follows the same cycle as the normal action of the engine by combustion.

The fluid pressure is discharged at the end of the stroke through the regular exhaust valve of the cylinder the same as the burned gas is discharged when the engine is running by combustion, there being no change in the operation of the inlet or exhaust valves.

The auxiliary starting device is provided with means whereby the communication between the distributing member and the traveling valve may be shifted from one cylinder to another in order to start the engine ahead or in the reverse direction. In the construction shown, this is accomplished through the agency of an intermediate part, or reversing member. The electrical timer is arranged in the same way, that is, so that the distributing contact-carrying member can be shifted; and the said distributing member and the reversing member of the device are connected together so that the movement of the single actuating device which performs all the functions necessary for starting the engine causes both the igniting devices and the air valve to be in the proper position to start and run the engine in whichever direction may be desired.

The cams which control the inlet and exhaust valves are arranged in pairs on sliding cam shafts, so that an endwise movement of the cam shaft will throw one set of cams or the other into operative position and thereby time the valves for operation in either direction. The sliding of the cam shafts is done by the same actuating device which controls the electrical timer and the auxiliary starting device, and also the means for operating the ignition mechanism.

The supply of compressed air is primarily controlled by a stop valve having an actuating device, so that the valve can be opened by hand to turn on the compressed air, pro-

vided the engine does not start in response to the ignition when the electrical timer is moved to starting position. This stop valve is preferably self-seating, it being necessary only to hold it open for a brief interval in order to insure the starting of the engine.

Figure 1 is a side elevation, partly in section, of a portion of an engine embodying the invention, showing the starting devices 10 and the cam shifting mechanism; Fig. 2 is a diagram showing, in a conventional way, the manner in which the pressure is distributed through the auxiliary starting device; Fig. 3 is an end elevation partly in section; Figs. 4 and 5 are horizontal sections, through the upper part of the auxiliary starting device, showing the reversing member in two different positions to start the engine ahead and reverse; Fig. 6 is a 20 vertical section, taken on line x^6 of Fig. 4, through the auxiliary starting device; Fig. 7 is a top plan view; and Fig. 8 is a horizontal section on the line x^8 of Fig. 1, part of the frame being broken away to show the 25 parts underneath.

The invention is shown as embodied in a six-cylinder four-cycle, single acting engine, the drawings, however, with the exception of the diagram, showing only a 30 portion of the cylinders, since all the operating mechanism in which the invention mainly consists is located at one end of the engine. In a six-cylinder engine with the cranks arranged in pairs 120° apart, there 35 will always be two cylinders in the sequence in which the pistons are respectively in favorable position to start the engine ahead or reverse, and, under normal conditions, if everything is tight, these two cylinders will 40 each contain a partially compressed charge of explosive mixture. By arranging the electrical timer, therefore, so that the distributing contacts can be moved a sufficient distance to cause a spark in either of two 45 successively operating cylinders, it is possible to produce ignition in either cylinder, and thereby to start the engine in either direction by combustion, if conditions are normal.

50 While any suitable or usual form of timer may be used without departing from the invention, the engine is shown as provided with a timer substantially like that shown and described in an application filed by us 55 May 4, 1908, Serial No. 430,881, and consists of a traveling contact member a and a member b carrying distributing contact members 1^b , 2^b , 3^b , 4^b , 5^b , and 6^b , best shown in Fig. 7. In this construction, the contact members are elongated for the purpose of insuring contact in the necessary cylinder for going forward or reversing; but while this construction is desirable for the reason that the engine will nearly always start by combustion on closing the circuit, it is not

essential to the engine embodying this invention, since the auxiliary starting device may always be relied upon, regardless of the system of ignition used. The contact member a is radially connected with a rotating shaft a^2 provided with a bevel gear a^3 which is in mesh with a bevel gear c connected or formed integral with a spur gear d which is arranged to drive one of the cam shafts, herein shown as the cam shaft d^2 which operates the exhaust valves of the engine.

The spur gear d is in mesh with the gear f which in turn meshes with the gear g^2 on the crank shaft g , the intermediate gear f also meshing with the gear h which controls the auxiliary starting device, as will be hereinafter described, as well as the inlet cam shaft h^2 . The gears are so proportioned that the cam shafts, the electric timer and the traveling valve make one revolution while the crank shaft makes two revolutions in a four cycle engine. The operation of the electrical timer, as well as that of the auxiliary starting device, may be best understood by reference to the diagram, Fig. 2, which shows the pistons in the position in which they are most likely to come to rest when the engine has been stopped by cutting off the ignition. The pistons are shown in this position for convenience in illustration and description, it being understood that the engine can be started with the pistons in any position in which they may come to rest.

The six cylinders are indicated by the numerals 1, 2, 3, 4, 5 and 6, and the firing sequence in the forward movement of the engine, starting from the position in which the air valve is shown, is 5, 3, 6, 2, 4, 1. These numerals, therefore, are used, in connection with a distinguishing reference letter, as indicating the distributing contact members of the electrical timer, as well as the corresponding distributing ports of the auxiliary starting device, the said electrical timer and the valve of the starting device operating in unison in accordance with the invention. Referring to the diagram, Fig. 2, the traveling valve i which is provided with the port i^2 , is shown with the said port i^2 in position to connect the source of compressed air with the cylinder 5, through the duct 3^1 , so that when pressure is admitted to the chamber below the valve, by opening the stop valve m , Fig. 3, the piston in cylinder 5 will be forced downward to start the engine ahead.

The downward movement of the piston in cylinder 5 turns the crank shaft in the forward direction, the piston in cylinder 3 then completing its compression stroke while the traveling valve i moves in the direction indicated by the arrow shown in full lines, to a position in which the port i^2 comes in line with the duct 3^1 leading to the cylinder

3, so that the compressed air is admitted to the said cylinder.

During the outward movement of the piston in cylinder 3, the piston in cylinder 6 has come to the end of its stroke ready for operation when the port i^2 reaches the duct 6¹ leading to the said cylinder. As will be seen from the diagram, the air is distributed to the cylinders in the proper sequence to produce the continuous operation of the engine. If the engine is to be reversed, the reversing member of the starting device is moved so that the port i^2 is placed in the relation to the distributing ports indicated by the dotted lines, so that when the stop valve m is opened, the cylinder 3 will be in communication with the source of compressed air, thus starting the engine in the reverse direction and producing the rotation of the member i in the direction of the dotted arrow. The cylinder 5 thus receives the next impulse, and is followed in turn by cylinders 1, 4, 2, 6, which is the reverse of the sequence named as the firing sequence for the forward movement of the engine.

The ignition timer which operates in the same cycle as the traveling valve above described is so arranged that in starting the engine the distributing timer member b is moved to a position in which the traveling contact member a will stand in contact with the distributing contact member 5^b or the distributing contact member 3^b, in one case to start the engine ahead and in the other case to start it in the reverse direction.

While the specific construction and arrangement of the electrical timer is not essential in the broader functions included in the present invention, and is fully described in the prior application above cited, it may be briefly stated that the distributing member b which carries the contacts 1^b, 2^b, &c., up to 6^b, is provided with a main operating handle b^2 which has a pivotal connection with the member b , and is adapted to close the electrical circuit at either one of the contacts b^3 by a rocking movement on said pivotal connection, it being impossible to impart such rocking movement to the handle, except when the distributing member b is in the proper initial position for starting ahead or starting in a reverse direction.

Under normal conditions, the engine will start on the spark, it being necessary only to move the handle b^2 to one or the other of its extreme positions, one movement causing the engine to start ahead, and the other causing the engine to start in reverse direction. At the end of such movement, the rocking movement of the handle b^2 is possible owing to the location of the slots or openings b^4 at the ends of the guide tongue b^5 which prevents such rocking movement when the handle b^2 is in any intermediate

position. The rocking movement of the handle b^2 closes the electrical contact at b^3 , so that the current through the system produces a spark in either cylinder 5 or cylinder 3, in accordance with the position of the handle; assuming, of course, that the engine has come to rest in the position indicated in the diagram, which position is the equivalent for any position in which the engine can come to rest so far as relates to the cycle of operations controlled by the sparking timer or the air valve. A spark will, therefore, be made in the right cylinder to start the engine, and the engine will start if ignition takes place. If, however, for any reason, such as an imperfect mixture, or leakage, or failure of the spark-plug in the starting cylinder, ignition does not take place, it is necessary to start the engine by fluid pressure.

In order that the auxiliary starting device may be properly positioned to start the engine, the said starting device is arranged to be operated by the handle b^2 so as to be set in the ahead or reverse position by the same movement which sets the electrical timer. For this purpose, the reversing member of the said device, which will hereinafter be described in detail, is connected by means of a link k with a radial arm connected with the supporting member or sleeve b^7 which carries the distributing member b of the electrical timer. Thus, the movement of the handle b^2 which places the engine in condition to start, correspondingly sets the reversing member of the auxiliary starting device, so that when the stop valve m is opened, the engine will run under the action of the compressed air, this operation taking place, however, without interfering with the normal operation which will be taken up as soon as a charge ignites in any cylinder. The stop-valve m is interposed between the compressed air inlet m^2 and the receiving chamber of the air distributing valve. This valve m is shown as mounted on a plunger m^3 and normally held seated by means of a spring m^4 , the air pressure also tending to hold the valve seated, as best indicated in Fig. 3.

The stem m^3 is located under an operating lever m^5 pivoted at m^6 , and arranged to bear upon the stem m^3 , so that by depressing the said lever, the pressure will be turned on, the valve being self seating, as soon as the lever m^5 has been released. In operating the engine, therefore, it is necessary only to move the handle b^2 to either of its extreme positions according to the direction in which the engine is to be started, and, if the engine fails to start upon completion of the circuit, the lever m^5 may then be depressed, whereupon the engine will start under the action of the compressed air, and continue to operate by compressed air as long as the

valve is held open. As soon as ignition takes place in any cylinder, the engine will operate in the normal way.

- In connection with the starting and reversing mechanism above described, it is also necessary to reverse the operation of the valve cams in accordance with the direction of movement of the engine. For this purpose, the inlet cams on the cam shaft h^2 and the exhaust cams on the cam shaft d^2 are arranged in pairs, there being two for each cylinder indicated as the inlet cams h^{20} , h^{30} , and the exhaust cams d^{20} , d^{30} . These cams are so arranged that a longitudinal movement of the cam shafts brings one set or the other into position to engage the valve stems, so that when the engine is to be reversed, it is necessary only to produce a longitudinal movement of each cam shaft. It is obvious that if the engine is equipped with automatic inlet valves, *i. e.*, check valves, it will be necessary to operate but one cam shaft, namely the one controlling the exhaust valves. To produce such longitudinal movement, the cam shafts are arranged to be actuated through the agency of the handle b^2 , the supporting member or sleeve b^7 being connected by means of a link b^8 with a lever b^9 which is pivotally supported between cam shafts d^2 and h^2 . This lever is provided at opposite ends with U-shaped recesses b^{10} and b^{12} which operate respectively upon pins d^3 and h^3 formed on sleeves connected with the cam shafts so far as relates to longitudinal movement, but arranged so that the cam shaft can rotate therein. As best shown in Fig. 8, therefore, the swinging movement of the lever b^2 produces a corresponding longitudinal movement of each cam shaft, the movements being in opposite directions, and the cams being arranged accordingly. In order to provide for such longitudinal movement without disconnecting the cam shafts from the gears by which they are driven, the said cam shafts are shown as provided with squared ends, and, for convenience, the construction of the cam shaft d^2 only will be specifically referred to, since that of the cam shaft h^2 is substantially the same. Said cam shaft d^2 is provided with a squared end d^4 which enters a correspondingly shaped socket in the gear d , which gear is provided with a suitable bearing and arranged, as previously stated, to make one rotation for each two rotations of the crank shaft. The longitudinal movement of the cam shaft d^2 , therefore, does not interfere with or prevent the normal rotary movement thereof in the operation of the engine.

It is necessary, for proper timing, that the traveling valve i should travel or rotate continuously, although, in the normal operation of the engine, this member performs no useful function. It is desirable, there-

fore, that the valve should be so arranged as to operate freely and without friction or wear, although it is necessary, when the valve is in use, to have tight joints in order to produce the proper distribution of the air without leakage and loss of pressure. To this end, the construction of the device is such that the traveling valve is out of contact with the stationary parts, except when the air pressure is turned on, but is so arranged as to be seated firmly by the air pressure while it is in actual operation.

Referring to Figs. 3 and 6, the valve i consists of a disk which is loosely connected with the rotating shaft i^2 driven by a bevel gear h^4 connected with the gear h , the said shaft being the same in construction as the shaft which operates the rotating member of the electrical timer. The said valve i is provided with a hub i^4 having slots in which fits loosely a transverse pin i^5 driven through the shaft i^2 , so that while the disk i is rotated by the shaft i^2 , it is free to move longitudinally with relation thereto.

The distributing ports 1^1 , 2^1 , 3^1 , 4^1 , 5^1 and 6^1 are formed in the stationary distributing member i^6 ; these ports, opening externally, as indicated at 7^1 , to receive the pipes leading to the several cylinders. Each of the distributing ducts is provided with a check-valve I between the valve and the cylinder to which it leads, the check-valves closing automatically when combustion takes place.

Interposed between the member i^6 and the valve i is an intermediate member n which may be described as the reversing member, the function of this member being to shift the communication from the air inlet to one or another of the outlet ducts, without changing the position of the rotary member i .

The member n is provided with a series of pockets n^2 , each pocket communicating with an inlet portion n^3 formed in the lower surface of the member n , said inlet portions being arranged in a circle so as to be consecutively brought into communication with the air inlet through the traveling port i^2 . Each of the pockets n^2 is of sufficient length to admit of the necessary reversing movement without losing communication through the duct to which it belongs. This member n is provided also with a stem n^4 having a radial arm n^5 which is connected with the link b^2 , so that the oscillating movement is imparted thereto by the action of the handle b^2 previously described as the operating or reversing lever for the engine. In order to reduce the size of the starting device, as a whole, as well as the area of the movable parts, the ducts in the stationary member are arranged in two concentric circles, and the pockets in the reversing member are arranged in the same way. By this construction, the ports directly controlled by the

valve can be arranged in a comparatively small circle, while the pockets which communicate with the several ducts can overlap, as best shown in Fig. 5, so that the whole device may be relatively small in diameter.

Referring to Figs. 4 and 5, it will be seen that, in Fig. 4, the port i^2 is in position to open communication between the source of compressed air and the pocket n^2 which communicates with the outlet passage 5^1 leading to cylinder 5. Upon starting the engine, communication will successively be opened to cylinders 3, 6, 2, 4 and 1, as shown in the diagram, Fig. 2. To reverse the engine, the member n is shifted in the direction of the arrow to the position shown in Fig. 5, so that the pocket n^2 in the member n which is in communication with the duct leading to cylinder 3 is brought into communication with the duct i^2 , so that communication is opened with cylinder 3. This starts the engine in the reverse direction, the sequence following in the reverse of that above set forth, i. e., 3, 5, 1, 4, 2, 6. In the construction shown, the port in the valve is so proportioned with reference to the distributing ports, that communication is established with a following cylinder in the sequence before it is cut off from the prior cylinder, so that it is impossible for the engine to stop in such a position that it will not start when the stop valve m is opened. The arm n^5 is so proportioned that the movement of the operating lever b to either starting position, correspondingly sets the auxiliary starting device for the necessary operation by fluid pressure, if necessary.

Both the member n and the member i are loosely mounted, and it is obvious that the air pressure will tend to press the said member i against the lower surface of the member n , thereby tightly sealing the joint between the two. This excess pressure is also sufficient to lift the member n into engagement with the upper surface of the casing, thereby resulting in the tight sealing of all the parts.

In the normal position shown in Fig. 6, the member n , which is normally stationary, rests upon a portion of the casing and is free from engagement with the upper surface i^7 , so that it affords no resistance to the shifting operation in starting the engine, and the member i , which is continually rotating, is out of engagement with the member n , and simply rests loosely upon a portion of the casing, or on the end of the shaft i^8 , so that no unnecessary friction is generated. The only time that any frictional resistance is encountered is when the air is turned on, and as this is only done in starting the engine, and usually not maintained for more than one or two strokes, there is very little wear on the parts.

Each one of the air ducts leading from

the stationary or distributing member i^6 of the air valve is provided with a check-valve, and the fluid pressure used is preferably somewhat lower than the expansive pressure caused by the exploding gases, so that, as soon as explosion takes place in any cylinder, the air pressure is cut off by the check valve, there being, therefore, no unnecessary waste of compressed air, and no discharge of burned or burning gases into the source of compressed air.

The operation of the device embodying the invention is as follows: To start the engine, the lever b^2 is moved from the position shown in the drawings to one or the other of the notches b^3 , to set the ignition timer, the auxiliary starting device and the valve cams according to the direction in which the engine is to run. The said handle is then raised to close the circuit, and if combustion takes place, the engine will start without the use of the auxiliary starting device. The initial movement of the handle b^2 , however, has set the exhaust cams in the proper position to operate the valves for ahead or reverse movement, as the case may be, as well as the inlet valves, if mechanical inlet valves are used. This movement has also properly set the reversing member of the auxiliary starting device, and if the engine fails to start after the circuit has been closed by raising the handle b^2 , the operator depresses the handle m^5 to open the stop valve m , whereupon the fluid pressure is admitted to the right cylinder to start the engine in the direction desired. This starting operation does not in any way interfere with the normal operation of the engine under its own combustion, so that, ordinarily the fluid pressure need be applied only for one or two strokes.

It is not intended to limit the invention to the specific construction and arrangement of the several instrumentalities which combine to form a complete starting mechanism, since modifications may obviously be made, without departing from the invention.

Claims.

1. In a multi-cylinder internal combustion engine, the combination with an ignition timer having a traveling contact member; and a distributing member of an actuating device for shifting said distributing member to time the ignition for operation in either direction; a source of fluid pressure; a distributing device having a stationary member provided with ports leading to the several cylinders, and a traveling valve having means for opening said distributing ports successively; means for changing the relation between said traveling valve and the distributing ports to correspond to the change in the electrical timer; and connecting mechanism between said electrical timer and said traveling valve whereby said parts

- are operated in unison by the actuating device aforesaid, substantially as described.
2. In an internal combustion engine, the combination with an ignition timer; of a source of fluid pressure; means for distributing said pressure to operate in the cylinder successively; common means for shifting the distributing member of said ignition timer and the distributing member of said pressure distributing means in unison for reversing the operation of the engine; exhaust-valves; means for opening said exhaust valves substantially at the end of the stroke during which the ignition timer and the pressure distributing means have operated; and shifting devices for the exhaust valve operating means actuated by the means for shifting the distributing members aforesaid. 70
- 10 3. In an internal combustion engine, the combination with an ignition timer; of an actuating member for the distributing device of the ignition timer whereby said distributing member can be set to start the engine ahead, or in a reverse direction; a source of fluid pressure; a traveling valve; a stationary distributing member; a reversing member connected with the distributing member of the ignition timer so as to be operated in unison therewith; and means whereby the traveling member of the ignition timer and the traveling valve also operate in unison, substantially as described. 75
- 20 4. The combination with the ignition timer having a traveling contact and relatively stationary distributing contacts; of a source of fluid pressure; a traveling valve operating in unison with the traveling member of the ignition timer; distributing ports successively opened by said valve, common means for shifting the order of operation of said distributing ports and that of the distributing contacts of the ignition timer; and a stop-valve to control the fluid pressure supply. 80
- 25 5. In a multi-cylinder internal combustion engine, a source of fluid pressure, and means for controlling the operation of said pressure comprising a stationary distributing member provided with ports leading respectively to the cylinders, said ports being provided with check valves; a rotary valve provided with a single port arranged to open communication successively through the distributing ports; a reversing member provided with ports adapted to shift the communication between the port in the rotating member and consecutive distributing ports; and means for shifting the position of said intermediate member. 85
- 30 6. In a fluid-pressure starting-device for internal combustion engines, the combination with a stationary distributing member provided with ports leading to the several cylinders; a traveling valve operating in unison with the half time shaft and provided with a single port, said valve being located above the air inlet and vertically movable within the valve casing; a reversing member for shifting the relation between the port in the rotary member and the distributing ports, said reversing member being also vertically movable in the casing; and means for oscillating said reversing member, substantially as and for the purpose described. 90
- 35 7. In an internal combustion engine having a plurality of cylinders, an exhaust valve for each cylinder; a longitudinally movable cam shaft provided with two cams differently positioned for each exhaust valve; means for moving said cam shaft longitudinally to bring one or the other of the sets of cams into operative position; an actuating device for producing the longitudinal movement of said cam shaft; an ignition timer provided with a distributing member capable of being shifted to admit of the reversal of the engine; an auxiliary fluid pressure starting device also having reversing means; and connecting mechanism whereby said actuating device also operates the distributing member of the timer, and the reversing means of the said fluid pressure starting device. 95
- 40 8. In a multi-cylinder, internal combustion engine, an ignition timer provided with a distributing contact member; an actuating device for said distributing contact member adapted to move said member from one position to another to time the engine for operation in either direction; a source of fluid pressure; a traveling valve operating in unison with the timer to distribute the fluid pressure to the cylinders; a reversing member coöperating with said valve, and connected with the actuating device for the distributing member of the ignition timer; and a longitudinally movable cam shaft also connected with said actuating device and provided with two differently arranged cams for the valve of each cylinder. 100
- 45 9. In an internal combustion engine, an auxiliary starting device comprising a source of fluid pressure; a distributing member having ports consecutively arranged and communicating with the several cylinders, the port in the traveling valve having a sufficient area to lap consecutive ports in the distributing member; and a reversing member adapted to shift the communication through the traveling valve from one distributing port to another. 105
- 50 10. In a starting device for internal combustion engines, the combination with a stationary distributing member having two sets of ports arranged in concentric circles; a reversing member capable of oscillating movement and having pockets also arranged 110
- 55 65 120
- 60 125
- 65 130

in concentric circles and adapted to lap adjacent ports in the stationary distributing member, and also being provided with inlets leading to said pockets, said inlets being arranged in a circle; and a rotating valve provided with a single port of sufficient length to lap adjacent inlet ports in the intermediate member.

11. In an internal combustion engine, an ignition timer having a plurality of distributing contacts, and means for shifting the position thereof to reverse the engine; a reversing cam shaft; an auxiliary fluid pressure starting device provided with reversing means; an actuating device; connecting mechanism whereby said actuating device is caused to operate said ignition timer, said cam shaft and the reversing means of the auxiliary starting device; and a separately operated stop valve for controlling the fluid pressure.

12. In an internal combustion engine, a reversing ignition timer; a reversing cam shaft; an auxiliary fluid pressure starting device provided with reversing means; a circuit closer for the ignition circuit; a common actuating device for said ignition timer,

said cam shaft, and the reversing means for the auxiliary starting device; and means whereby said actuating device is caused to operate said circuit controller at the end of the movement which operates the reversing mechanism.

13. In an internal combustion engine, igniting devices; reversible means for timing the ignition; a reversing cam shaft; an auxiliary fluid pressure starting device provided with reversing means; means for operating the igniting devices; a common actuating device for said means for timing the ignition, said cam shaft and the reversing means for the auxiliary starting device; and means whereby said actuating device causes the operation of the igniting devices after the movement which operates the reversing mechanism has been completed.

In testimony whereof, we have signed our names to this specification in the presence of two subscribing witnesses.
